UNITED STATES PATENT OFFICE.

HARRY W. TITGEN, OF PHILADELPHIA, PENNSYLVANIA.

TUMBLING MILL.

Application filed February 25, 1926. Serial No. 90,577.

My invention relates to tumbling mills, and it has for one object the provision of a continuously operating mill wherein the material to be cleaned, as well as the cleaning elements, may be introduced at one end of the mill and positively fed therethrough to the discharge end, the cleaning elements being automatically returned to the entrance end, whereby a continuous supply of cleaning elements may be had so long as the mill is operated.

Another object of my invention is to provide a tumbling barrel shell of such form that upon a movement thereof, the castings to be cleaned, as well as the cleaning jacks, are automatically fed through said shell from the entrance end to the discharge end.

A further object of my invention is to so associate the suction pipe and the hopper outlet that the latter is prevented from completely filling up the suction pipe.

Other objects and applications of my invention, as well as details of construction and operation, whereby my invention may be practiced, will be apparent more fully hereinafter, when taken in connection with the accompanying drawings, wherein

Fig. 1 is a side elevational view of a tumbling mill embodying my invention,

Fig. 2 is a horizontal sectional view of the structure of Fig. 1, the sectional plane being taken on the line 2—2 of Fig. 1,

Fig. 3 is an end elevational view of the structure of Fig. 1, looking from the right and

Fig. 4 is a transverse sectional view taken on the line 4—4 of Fig. 2.

In the illustrated embodiment of my invention shown in the drawing, a tumbling mill 1 comprises an inner shell or drum 2, having an inlet opening 3 at a smaller end 4 for the reception of castings to be cleaned and a discharge outlet 5 at a larger end 6. Experience has shown that when a shell of such form is filled with material to be cleaned, as for example, radiator castings 7 and cleaning or abrasive means 8, the movement of the shell causes the castings 7 and cleaning means 8 to be automatically fed therethrough.

The tapered shell 2 comprises a perforated section 9 at the smaller end 4 thereof through which the cleaning means or jacks 8 are automatically fed in a manner that will presently appear; a perforated section 10 adjacent to the larger end 6; and an intermediate im-

perforate section 11, which constitutes the principal abrasive or cleaning chamber. The perforated section 10 comprises a section 12 having relatively fine perforations 13 through which the material that is removed from the castings 7 may pass. The section 10 also comprises an adjacent section 14 wherein the perforations 15 are of increased size, so that the smaller of the jacks 8 may pass therethrough, the remaining jacks 8 passing through the larger perforations 16 of a perforated portion 17 of section 10 which is disposed at the end of the shell 2. The jacks 8 are thus gradually removed from the shell 2 as they approach the discharge outlet 5 thereof, only the larger of the jacks reaching the perforated portion 17 of section 10.

A plurality of longitudinally extending strips 18 may be mounted on the inner side of tapered shell 2, so that the castings 7 and jacks 8 may be lifted upon the movement of shell. Such sand as still adheres to the castings 7 as they approach the discharge outlet 5 may be removed by causing said castings to be raised to an elevated position and then permitted to fall so as to turn end for end. This desired result may be accomplished by a plurality of angularly disposed members 19, a vertical wall 20 of each being positioned as shown in Figs. 1 and 4 so as to exert a lifting and turning action as the tapered shell 2 rotates. The new position assumed by the castings after being actuated by the members 19 is illustrated at 21 in Fig. 2.

In accordance with my invention, the jacks 8, which pass through the perforated section 17, at the discharge end 6 of shell 2, are automatically conveyed by means of a conveyor shell or drum 22 to the perforated section 9 at the entrance end 4 of the shell 2, whereby a self-contained, continuously operating tumbling mill may be had. To this end, I have so designed the outer conveyor shell 22 that the respective ends 23 and 24 thereof surround the perforated section 17, through which the jacks pass from the shell 2, and the perforated section 9, through which the jacks enter the inner shell 2. The respective ends 4 and 5 of the inner shell 2 may be rigidly secured to the adjacent ends of the outer casing 22 by means of annular plates 25 and 26, which also serve to close the ends of an annular chamber 27 that is formed between the inner and outer shells 2 and 22.

The movement of jacks 8, immediately on entering the conveyor shell 22, may be facili-

tated by tapering a section 24^a thereof oppositely with respect to the inner shell 2. The further movement of the jacks 8 to the entrance end 4 of the inner shell 2 may be brought about by means of spiral flails 28 which may be mounted on the inner walls of the outer conveyor shell 22. The flails 28 immediately adjacent to the perforated section 9 are provided with enlarged sections 28^a whereby the jacks 8 may be lifted as the conveyor shell 22 rotates and permitted to fall under the action of gravity through the perforated section 9. The lifting of the jacks 8 may be further facilitated by means of a plurality of lifting flights 30, of which three are shown in Fig. 3. Should the jacks 8 tend to fall out the inlet opening 3 of the tapered shell 2, a tubular extension 31 may be mounted at this point, as shown in Fig. 2.

The material removed from the castings 7 during the grinding or abrasive operation passes through the perforated section 10 of the tapered shell 2 into the conveyor shell 22. In order that this material may be removed from said conveyor shell 22, an intermediate section 32 thereof is provided with a plurality of perforations 33. The section 32 may be enclosed by a housing 34, as shown in Fig. 1, the upper portion 35 of which is provided with an outlet 36, leading to a suction fan (not shown), so that the dust incident to the abrasive operation may be removed. The heavier portions of the material removed from the castings 7 pass into a hopper section 37 of the housing 34. The hopper 37 has an elongated outlet 38, which extends part way into a suction pipe 39 in the manner indicated in Fig. 3, so that under all conditions of operation the suction pipe 39 is not completely closed, but a space 40 is left permitting the free passage of air. Access may be had to the suction pipe 39, for purposes of cleaning, through a removable cover 41.

The outer conveyor shell 21 is provided with a pair of spaced tires 42 and 43, which are respectively mounted on pairs of anti-friction rollers 44 and 45. The rollers 44—44 are mounted on a single shaft 46 journaled in bearings 47 of usual design. The other pair of rollers 45—45 are similarly mounted on a shaft 48 supported by journals 49, as illustrated in Fig. 3. The shaft 48 may be operated by means of an electric motor 50 through a reduction gear-wheel mechanism 51 and a flexible coupling 52. The rotation of the conveyor casing 22, by the shaft 48, may be rendered more positive by means of a driving pinion 53 and a gear-wheel 54, the latter being mounted on the outer conveyor shell 22.

Assuming the conveyor shell 22 to be rotating, and a constant quantity of jacks 8 supplied to the entrance end 4 of the ta-

perated shell 2 by means of the flails 28 and flights 30, when the castings 7 are inserted in this end of the shell 2, the continued turning of said tapered shell 2 causes an automatic movement of the castings 7 and jacks 8 toward the discharge end 6. As the castings 7 and jacks 8 are passed through the principal working chamber and the perforated section 10 of the tapered shell 2, the castings are thoroughly cleaned. The resulting dirt and dust passes principally through the perforated section 12 and the perforations 33 of the conveyor shell section 32 into the housing 34, whereupon the lighter dust passes out through the discharge outlet 36, while the heavier materials are removed through the suction pipe 39.

When the jacks 8 have been moved into the section 14, they pass from the tapered shell 2 into the outer conveyor shell 22, the castings 7, however, being discharged through the outlet opening 5. The jacks 7, by reason of the tapered section 24^a of the conveyor shell 22 and the flails 28 and lifting flights 30, are again discharged through the perforated section 9 into the inlet end of the inner shell 2, thus being again available for further use. Hence the operation of the tumbling mill 1 is continuous and need not be interrupted while the jacks are being conveyed from the discharge end 6 of the mill to the entrance end 4.

While I have shown only one form of the embodiment of my invention, for the purpose of describing the same and illustrating its principles of construction and operation, it is apparent that various changes and modifications may be made therein, without departing from the spirit of my invention, and I desire, therefore, that only such limitations shall be imposed thereon as are indicated in the appended claims or as are demanded by the prior art.

I claim:

1. A tumbling barrel shell of tapered form provided with inlet and outlet openings, said shell having perforated sections respectively adjacent to said openings, so that the cleaning means may be discharged at one opening and received at the other, said shell having an intermediate imperforate section constituting a cleaning chamber, and means whereby the articles to be cleaned may be lifted upon the movement of said shell.

2. A tumbling mill comprising a tapered inner shell having entrance and discharge openings, said shell being also provided with perforated sections adjacent to the respective ends thereof, a conveyor shell operatively associated with said perforated sections, and means whereby the material passing through the perforated section adjacent to the discharge end may be positively conveyed to the perforated section adjacent to said entrance end.

3. A tumbling mill comprising a tapered inner shell having an inlet opening at one end and a discharge opening at the other end, said shell being provided with perforated sections adjacent to the respective ends, and an outer shell for conveying the cleaning means passing through one perforated section to the other perforated section, said outer shell being so perforated 10 that undesirable materials may be removed therefrom.

4. A tumbling mill comprising an inner shell provided with perforated sections adjacent to the respective ends thereof and an intermediate section constituting an abrasive chamber, an outer conveyor shell for positively conveying the cleaning means passing through one perforated section to the other perforated section, and means whereby 15 undesirable materials may be removed from 20 said outer shell.

5. A tumbling mill comprising an inner shell of tapered form provided with perforated sections adjacent to the respective 25 ends thereof and also an intermediate imperforate section, an outer conveyor shell having a tapered portion in operative relation to one of said perforated sections and another portion in operative relation to the 30 other perforated section, and means whereby the cleaning elements passing through one perforated section may be positively fed to the other perforated section and passed therethrough.

6. A tumbling mill comprising a tapered inner shell provided with spaced perforated sections and also an imperforate section constituting the principal working chamber, an outer shell in operative relation to said perforated sections, and spiral conveying means 40 positioned intermediate said shells, so that the cleaning elements passing through one perforated section may be returned to the other perforated section and passed therethrough. 45

7. A tumbling mill comprising a shell provided with a tapered section, said shell also having perforate sections, a conveyor shell having one section thereof oppositely tapered and positioned to receive the cleaning elements passing through one of said perforated sections, another section of said conveyor shell being in operative relation to the remaining perforated section, and conveying means disposed in the last-mentioned section 50 of said conveyor shell. 55

8. A tumbling mill comprising an inner shell provided with perforated sections adjacent to the respective ends thereof and an intermediate section constituting an abrasive chamber, at least a portion of one of said sections being tapered, means including an outer conveyor shell for positively conveying the cleaning means passing through one perforated section to the other perforated section, and means whereby undesirable material 60 may be removed from said outer shell. 65
